Filed Mar. 27, 1969, Ser. No. 16,472

Term of patent 14 years

Int. Cl. D12—11

U.S. Cl. D90—8

FIG. 1 is a perspective of a frame for bicycles constituting my new design;

FIG. 2 is a right side elevation view, the left side elevation view being substantially a mirror image thereof;

FIG. 3 is a plan view;

FIG. 4 is a cross-section taken through line 4—4 of FIG. 3, looking in the direction of arrows 4—4; and

FIGS. 5 and 6 are end views looking in the direction of arrows 5—5 and 6—6, respectively, of FIG. 2.

The elements of a bicycle shown in broken lines are included for illustrative purposes only.

I claim:

The ornamental design for a frame for bicycles, substantially as shown and described.
